UNITED STATES PATENT OFFICE.

RAUL PATERAS PESCARA, OF BARCELONA, SPAIN.

PROPELLER WITH HELICOIDAL TORSION.

Application filed February 28, 1921. Serial No. 448,645.

To all whom it may concern:

Be it known that RAUL PATERAS PESCARA, citizen of Argentina, residing at Barcelona, Spain, Calle Buenasuerte 20 (S. M.), has 5 invented certain new and useful Improvements in Propellers with Helicoidal Torsion, of which the following is a specification, reference being had therein to the accompanying drawing.

10 This invention relates to an improvement in flying machines of the helicopter type, and is particularly directed to a construction wherein the efficiency of the propeller is materially increased through the control 15 of the helicoidal torsion.

In an application filed by me February 28, 1921, Serial No. 448,646, I have described a multi-plane propeller in which means are provided for controlling the twisting of the 20 blade, and the present application is directed more particularly to the specific means for this purpose, which is generally described in the above noted application.

In the drawings:

25 Fig. 1 is a view in elevation of a multi-plane propeller constructed in accordance with the present invention.

Fig. 2 is a plan of one of the blades, the covering being removed.

30 Figs. 3 and 4 are respectively plans and transverse sections illustrating the torsion modifying means.

Fig. 5 is a transverse section through one of the blades.

35 As set forth in the application above referred to, the present propeller is shown as of the biplane type with lower and upper blades 10 and 11 radiating from an enlargement 8 of a hub 9 and connected by struts

40 12 having diagonal tie rods 13. Each blade is made up of a frame connected by ribs 23, which as indicated in Fig. 5, are each formed of a wooden web 24 exteriorly strengthened by a wooden ledge 25. Tubes 26-27 pass 45 through and connect the ribs. The blade is rotatably supported on a shaft 28 and held thereon against endwise movement by ball bearings 31-32. Special ribs 29 are provided through which the shaft 28 passes 50 and in which it may be mounted through bronze bearings.

A cable 34 extends longitudinally of the blade and is connected to suitable operating mechanism arranged in the enlargement 8 of the hub 9, so that the cable may be drawn 55 upon at will, or relieved of such tension

as may be desired. The cable is designed to operate certain screw elements for imparting a torsion or twisting movement to the blade, these screw elements being more particularly shown in Figs. 3 and 4. The screw elements constitute a member including encircling and free bearing sleeve portions 38-39, which embrace the shaft 28, and arms 32 extending therefrom to a portion 60 having rigid connection with the tube 26. This member is formed adjacent the tube 26 and centrally between the arms 32 with the section 40 having a worm tooth formation 65 on its inner edge. The cooperating member 70 includes a segment portion 31 having a threaded surface cooperating with the worm thread surface of section 40, this member 31 being pivotally supported at 35 upon a pin 36 extending transversely through the 75 shaft 28. The member 31 is extended beyond the pivot 36 in the form of an arm to be connected at 37 to the cable 34.

Obviously, in movement of the cable, a 80 corresponding movement is imparted to the elements 31, which through the worm and thread connection, with the tube 26, that is, with the blade proper, a twisting or torsional movement is imparted to said blade.

If it is desired to provide a variation of 85 the helicoidal torsion of the blade surface, the successive endless screw members may be given different pitch, whereby various sections of the blade are given a variable torsion or twisting, as will be evident.

90 Through this control, it is apparent that the blades may be operated plain, that is, without torsion, through the identical pitch of the respective screw elements 31 or may be given any degree of torsion, either negative 95 or positive within the range of the screw members, and this torsion may be varied for different sections of the blade, all as will be understood from the above description.

The negative torsion is particularly desirable 100 in the descent of the machine in rotative gliding flight; while positive torsions are particularly desirable in forward driving and in landing, it being highly important under the latter condition that the torsion of the blades which was negative during descent is made suddenly positive just before landing, thereby utilizing the energy 105 stored in the blades during their rotation in descent to neutralize the similar energy of the machine as a whole and thus avoid landing shock.

Claims:

1. A helicopter having propellers, the blades of each propeller being mounted for movement about a shaft, screw members supported for pivotal movement on the shaft, a cooperating worm thread member rigid with the blade, and a cable for simultaneously operating all of said screw members, whereby to impart a twisting action to the blade with respect to the shaft.
2. A helicopter having propellers, the blades of each propeller being mounted for movement about a shaft, screw members supported for pivotal movement on the shaft, a cooperating worm thread member rigid with the blade, and a cable for simultaneously operating all of said screw members, the pitch of the thread of the screw members of any one blade being relatively different to impart different twisting action to the respective sections of the blade by the simultaneous operation of the screw members.
3. A propeller for aircraft, including a blade supporting bar, a blade rotatable thereon, a member mounted on the blade
- 5 having a worm thread and a rotatable connection with the bar, a member pivotally mounted on the bar provided with a worm thread cooperating with the worm thread of the first member, and means for operating the pivoted member to partially rotate the blade on the bar.
4. A propeller blade mounting, including a blade carrying bar, a blade rotatable thereon, members carried by the blade, each having a worm thread and spaced arms rotatably mounted on the bar, members pivotally mounted on the bar between the arms of each blade carried member and having a worm thread cooperating with the worm thread of the blade carried member, and operating means for the pivotal members for imparting a movement to the blade relative to the bar.
- 10 In testimony whereof he affixes his signature in presence of two witnesses.
